UNITED STATES PATENT OFFICE.

WILLIAM W. SHOE, OF WALLINGFORD, PENNSYLVANIA.

BICYCLE-SADDLE.

SPECIFICATION forming part of Letters Patent No. 558,217, dated April 14, 1896.

Application filed September 16, 1895. Serial No. 562,608. (No model.)

To all whom it may concern:

Be it known that I, WILLIAM W. SHOE, a citizen of the United States, residing at Wallingford, in the county of Delaware and State 5 of Pennsylvania, have invented certain new and useful Improvements in Bicycle-Saddles; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 My invention relates to bicycle-saddles; and the object of my invention is to provide a simple and effective means of tightening the spring, and thereby taking up the stretch of the leather seat.

20 I accomplish the desired result by securing a movable hook to the under side of the plate on the front end of the saddle and moving said hook back and forward by means of a screw passing through it, the open end of said hook fitting over a loop formed on the front end of the saddle-spring and the whole device 25 arranged and secured to the saddle in the manner hereinafter described, and particularly pointed out in the claim.

30 In the accompanying drawings, Figure 1 is a lengthwise sectional view of the front end of a bicycle-saddle having my improvement attached thereto. Fig. 2 is an inverted plan view of the front end of the saddle. Fig. 3 is 35 a vertical sectional view of the plate fastened to the front end of the saddle, the hook holding the front end of the saddle-spring, and the screw by means of which the hook is moved back or forward.

40 A represents the leather seat of the saddle. B is a steel plate securely fastened to the front end of the saddle by means of the rivets *a a*.

45 *b b'* are the front and rear ends of the plate B, bent at right angles thereto and bored out to fit the ends of screw C.

a' is a depression formed lengthwise in the plate B.

D is a screw-threaded hook fitting on the screw C. 50

d is a slot cut in the top of the hook D and fitting in the depression *a'* on the plate B.

b² *b³* are shoulders formed on the front and rear ends of the screw C.

c is a square end on the screw C to allow a 55 key or wrench to be fitted thereto.

E is the steel saddle-spring. If desired, this spring may be made of a flat piece of steel instead of the round wire shown.

d' is a loop or hook formed on the front end 60 of the spring E.

When the several parts of the saddle are constructed in the manner shown and described, if it is desired to take up the stretch in the leather seat A the screw is turned so 65 as to move the hook C to the rear of the saddle. This movement will have the effect of bending and thereby stiffening the steel spring E, forcing it to take up any slack or stretch in the leather. The slotted top of the 70 screw-threaded hook D fitting over the depression *a'* in the plate B, the hook cannot turn around, but must move forward or backward in a straight line when the screw is turned. The top of the hook D, bearing 75 against the under side of the plate B, prevents the screw C from bending in the direction of the plate.

Having thus described my invention, what I claim as new, and desire to secure by Letters 80 Patent, is—

In a bicycle-saddle, the combination of the plate B, secured on the front end of the saddle and having therein the depression *a'*, the screw C, fitting into the plate B, the screw-threaded hook D, having therein the slot *d*, and the spring E, having on the front end thereof the loop *d'*, substantially as and for the purpose described. 85

In testimony whereof I affix my signature 90 in presence of two witnesses.

WILLIAM W. SHOE.

Witnesses:

THOS. D. MOWLDs,
SAML. H. KIRKPATRICK.
